UNITED STATES PATENT OFFICE.

HOMER M. LEONARD, OF SAN FRANCISCO, CALIFORNIA, ASSIGNOR TO WILLIAMS BROS.
AIRCRAFT CORPORATION, OF SAN FRANCISCO, CALIFORNIA, A CORPORATION OF
CALIFORNIA.

DESIGN FOR A TRAFFIC SIGNAL.

Application filed February 4, 1925. Serial No. 12,262. Term of patent 3½ years.

To all whom it may concern:

Be it known that I, HOMER M. LEONARD, a citizen of the United States, residing at San Francisco, in the county of San Francisco and State of California, have invented a new, original, and ornamental Design for Traffic Signals, of which the following is a specification, reference being had to the accompanying drawing, forming part thereof.

Fig. 1 is a front elevation; Fig. 2, is a top plan; and Fig. 3 is a side elevation of a traffic signal, showing my new design.

I claim:

The ornamental design for a traffic signal, as shown.

HOMER M. LEONARD.
